UNITED STATES PATENT OFFICE

2,595,097

WRITING AND DRAWING IMPLEMENT

Lewis A. Paul, Wichita, Kans., assignor to Beech Aircraft Corporation, Wichita, Kans., a corporation of Delaware

Application December 9, 1947, Serial No. 790,457

3 Claims. (Cl. 120—48)

1

The invention here disclosed relates to writing and drawing implements of the reservoir or fountain pen type.

More particularly, the invention relates to pens of the character disclosed in copending patent applications Serial No. 740,055, filed April 8, 1947, now Patent 2,495,179 and Serial No. 786,179, filed November 15, 1947, in which the feed of ink to the writing or drawing point is governed by capillary flow.

Constancy and continuity of line is attained in these pens through the use of a special quick drying lacquer.

The use of this lacquer involves certain control factors and it is the general purpose of the present invention to provide satisfactory mechanism for accomplishing such control.

More specifically, it is a purpose of the invention to provide simple and effective means for regulating and controlling the ink flow in a pen of the capillary type indicated.

Other important objects of the invention are to provide the means referred to in simple, inexpensive and thoroughly reliable form.

Other desirable objects attained by the invention are indicated or will appear in the course of the following specification in which the novel features of the invention are described and claimed.

The drawing accompanying and forming part of the specification illustrates one present practical embodiment of the invention. Structure, however, may be modified and changed as regards the immediate illustration, all within the true intent and broad scope of the invention as hereinafter defined and claimed.

Fig. 1 in the drawing is a side elevation of a drawing, writing and ruling pen having features of the invention incorporated therein, with parts broken away and appearing in section;

Fig. 2 is a longitudinal sectional view of the pen;

Fig. 3 is a side elevation of the inner barrel, cylinder or body member;

Fig. 4 is a similar view of the adjustable piston member;

Figs. 5, 6, 7 and 8 are enlarged cross sectional views as on those numbered lines in Fig. 2;

Fig. 9 is a further enlarged broken sectional detail of the capillary writing, ruling or drawing point.

The structure shown is of the same general design as that disclosed in the earlier filed patent application Serial No. 740,055 now Patent 2,495,179, to the extent of comprising an inner cylinder member 10, a surrounding sleeve 11, a

2

piston 12 adjustable in the cylinder through the medium of a cap 13 rotatably mounted on the upper end of the barrel structure and a capillary writing point 14 carried by a ferrule 15 screwed over the feed tube extension 16 at the lower end of the inner or cylinder portion 10 of the barrel.

Also, as in the former patent application, longitudinal motion is imparted to the piston by having the stem of the piston screw threaded at 17 to match internal screw threads 18 in the end cap 13, and by slotting the piston stem at 19 to receive the cross pin or key 20 carried by collar 21 screwed fast on the end of the barrel and carrying the balls 22 rotatably confining the cap 13 in the end of the collar.

The feed tube 16 on the end of the barrel has a flow passage 23 of cross sectional dimension to freely pass the ink to the capillary point and, when the capillary point is removed, to permit quick emptying or filling of the ink barrel by simply operating the piston to expel or draw in the ink, as desired.

Under some drawing conditions, and particularly with the use of the special quick drying lacquer described, it has been found that more positive and accurate control of ink flow can be effected by venting the ink column in the inner barrel to admit atmospheric pressure to the top of the writing fluid.

The structure for such purpose involves, in the illustration, the provision of a small vent hole or holes 24 in the lower end portion of the inner barrel, opening to an annular space 25 between the inner and outer barrel members 10, 11, and the connecting of this annular space through ink flow restricting, small air passages 26 with an annular air relief 27 at the upper end of the barrel which can be opened to atmosphere through a port 28 under control of a ball valve 29.

The latter is shown partially contained and held in a seat 30 formed in the encircling split ring or band 31 which is confined for limited rotational movement on the outer barrel or sleeve 11 by reason of the ball engaging in tapering grooves 32 of limited circumferential extent.

The spring of the encircling band 31 is sufficient to hold the ball 29 closed to its seat 28 in the intermediate position illustrated and to frictionally retain the ball in position at either side 50 of the valve seat center, that is, in fully closed or partially or fully opened positions.

The ink flow restricting but air venting passages 26 are shown provided by small longitudinal grooves in the elongated, full diameter portion 33 of the inner barrel which closely fits the

inside of the outer barrel 11, and the annular air relief is shown provided simply as an annular groove 21 at the upper end of the full diameter portion of this member.

Full diameter lands 34 and 35 at the lower and upper ends of the inner barrel enable firm, close fitting engagement of the outer barrel or sleeve member 11. The valve ring 31 may be turned to open or close the air vent 28 at any time regardless of and independently of the action of the piston 12, thus to vary flow conditions and obtain desired effects at the writing or drawing point.

The main body of ink within the barrel is open to the surrounding annular chamber 25 but flow of such ink to the vent controlling valve 29 is prevented by the flow restricting channels 26, while limited passage of air is permitted. Hence the air vent may be controlled one way or the other without escape of the writing fluid.

Air pressure on the ink column may thus be adjusted as required to effect different desired results and to maintain continuous lines of substantially uniform density and width.

The instrument thus is particularly well adapted for rapid, accurate, durable precision drawing work, and it may be used for writing as well as for ruling or drawing purposes.

The parts are few in number, of simple, substantial design and not such as might readily get out of order. Also, the structure is easily assembled and can be produced at reasonably low cost. Different writing points may be quickly interchanged and the construction disclosed provides for exercise of proper control to suit conditions introduced through use of different writing or drawing points.

With adjustment of the piston, any desired positive pressure may be applied to the ink column and this may be modified or reduced as desired, by adjustment of the air vent valve to effect smooth, continuous flow at the writing or drawing point. The small vent slots in the sides of the inner barrel may be of capillary size.

What is claimed is:

1. An instrument of the character disclosed comprising an inner ink barrel, a capillary flow feed point at the lower end of the same, an outer barrel surrounding said inner ink barrel and providing therewith an annular chamber, said inner barrel having a vent passage in the side and near the lower end of the same but above said capillary flow feed point opening to said annular chamber, an ink flow restricting air passage between said inner and outer barrels extending from said annular chamber, a valve port in the outer barrel near the upper end of the same in

communication with said restricted air passage and a valve cooperable with said port.

2. An instrument of the character disclosed comprising an inner ink barrel, a capillary flow feed point at the lower end of the same, an outer barrel surrounding said inner ink barrel and providing therewith an annular chamber, said inner barrel having a vent passage in the side and near the lower end of the same but above said capillary flow feed point opening to said annular chamber, an ink flow restricting air passage between said inner and outer barrels extending from said annular chamber, a valve port in the outer barrel near the upper end of the same in communication with said restricted air passage and a valve cooperable with said port and including a ball and a spring band encircling said outer barrel and having a seat confining said ball to rotatable movement with said band.

3. An instrument of the character disclosed comprising an inner ink barrel, a capillary flow feed point at the lower end of the same, an outer barrel surrounding said inner ink barrel and providing therewith an annular chamber, said inner barrel having a vent passage in the side and near the lower end of the same but above said capillary flow feed point opening to said annular chamber, an ink flow restricting air passage between said inner and outer barrels extending from said annular chamber, a valve port in the outer barrel near the upper end of the same in communication with said restricted air passage and a valve cooperable with said port and including a ball and a spring band encircling said outer barrel and having a seat confining said ball to rotatable movement with said band, said outer barrel having tapering grooves of limited circumferential range extending from said valve port to receive said ball and thereby limit the rotatable movement of said spring band.
